(57) **CLAIM**

We claim the ornamental design for a bubble generating vacuum toy, as shown and described.

DESCRIPTION

FIG. 1 is a top left and front perspective view of the bubble generating vacuum toy showing our new design; FIG. 2 is a top right and rear perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines are included for the purpose of illustrating portions of the bubble generating vacuum toy including surface details that form no part of the claimed design.

The appearance within the unshaded regions recessed within the openings showing in FIGS. 2 and 6 likewise forms no part of the claimed design.
